No. 787,372.

PATENTED APR. 18, 1905.

W. GILES & H. RAMSEY.
BURGLAR AND FIRE ALARM.
APPLICATION FILED SEPT. 30, 1904.

UNITED STATES PATENT OFFICE.

WILLIAM GILES AND HENRY RAMSEY, OF MAMMOTH, WEST VIRGINIA.

BURGLAR AND FIRE ALARM.

SPECIFICATION forming part of Letters Patent No. 787,372, dated April 18, 1905.

Application filed September 30, 1904. Serial No. 226,669.

To all whom it may concern:

Be it known that we, WILLIAM GILES and HENRY RAMSEY, citizens of the United States, residing at Mammoth, in the county of Kanawha and State of West Virginia, have invented certain new and useful Improvements in Burglar and Fire Alarms, of which the following is a specification, reference being had therein to the accompanying drawings.

10 Our invention relates to door and window stops and alarms, and more particularly to that class wherein a stop of the character described is connected with an electrical alarm attachment, the object of the invention being 15 to provide a device of the character described that shall be simple and inexpensive in construction, durable, and effective in operation and that can be readily adjusted to any door or window in such manner that the pressure 20 thereof upon the stop will close the circuit and cause an alarm to be sounded.

A further object of our invention is to provide a device of the character described that can also be used as an effectual alarm in case 25 of a fire.

In the drawings accompanying this specification and made a part hereof we have illustrated a preferred embodiment of our invention, and while changes of detail will be suggested to one skilled in the art such changes or modifications come well within the scope and spirit of our invention as disclosed and claimed, and we do not, therefore, desire to be limited to the exact construction shown.

35 In the drawings, Figure 1 is a perspective view of the corner of a room, illustrating our improved alarm in position. Fig. 2 is a horizontal section taken through the means for connecting the alarm with a door. Fig. 3 is 40 a similar view showing the same applied to a window. Fig. 4 is a detail section showing the upper-wire support.

Like reference-numerals designate corresponding parts in all the figures of the drawings.

1 designates a stop pivotally mounted on a projecting lug or cleat 2, secured to the wall adjacent to the door. This stop is provided with a pin 3, having a sharpened point 4.

50 The pin 3 works within a hole 5 in the stop,

being held in place by means of a small lug or pin secured thereto which works in a slot cut in one side of the stop. Secured to the stop, on each side of the hole 5, is a small plate 6, which projects over the hole, leaving 55 a small space for the reception of the point 4. To each plate is secured a wire 7, which connects with a battery 8, the battery being connected with a bell or buzzer 9. When the door 10 is opened, it comes in contact with 60 the pin 3, pushing it forward. This movement brings the point 4 into engagement with the plates 6 and closes the circuit by reason of the connection of the wires 7 with the battery and causes the alarm to be sounded by 65 the bell or buzzer. It will be observed that by reason of the stop 1 being pivotally mounted on the lug 2 it can be pulled out of the way of the door during such times as it is not needed, so that it will not interfere with the 70 free opening and closing thereof.

11 designates a stop similar to stop 1. This stop is secured to the window-frame adjacent to the sash and is provided with the same circuit-closing arrangement as stop 1, in which 75 12 designates the pin, 13 the point, and 14 the plates to which the insulated wires 7 are secured, these wires being connected with the battery 8. A projecting lug or arm 15 is pivotally mounted on the window-sash, so that 80 when same is not in position for operation it can be pulled to one side, permitting free operation of the window-sash. When an attempt is made to raise the sash, this lug, being in operative position, is brought into contact with the bottom of the pin 12, pushing the same upward, bringing the point 13 into engagement with the plates 14, thus closing the circuit and causing the alarm to be sounded by 85 means of the bell or buzzer 9. 90

16 designates hooks depending from the walls of the room in which our device is used. A thread or cord 17 is stretched across the hooks and acts as a support for the upper wire. When a fire occurs, the thread or cord 95 is quickly burned away, causing the upper wire to fall into the hook 16, thus closing the circuit and sounding the alarm by means of the bell or buzzer.

It will be readily observed that the battery 100

and bell can be placed where desired in a room, either above, below, or opposite a door or window, or they can be placed in a house or building at a distance from the one in which the devices shown in Figs. 2 and 3 are placed. For illustration, the said devices illustrated in Figs. 2, 3, and 4 can be placed in a factory, store, or shop and the battery and bell in a residence in such position as to immediately sound an alarm in case of fire or burglary.

Having thus described our said invention, what we claim as new, and desire to secure by Letters Patent of the United States, is—

15 1. A combined window-stop and alarm comprising a pivotally-mounted stop, a pin slidably mounted in a hole in the stop, a plate arranged on the stop on either side of the hole, a point on the pin arranged to engage with the plates and close the circuit, a battery, a bell, a plurality of wires connecting the bell, battery, and plates, so that when the point on the pin engages the plates, it closes the circuit and rings the bell, substantially as described.

20 2. A combined window-stop and alarm comprising a pivotally-mounted stop, a pin slidably mounted in a hole in the stop, a lug on the pin arranged to slide within the slot in the stop and to hold the pin in place, a plate arranged on the stop on either side of the hole, and a point on the pin arranged to engage the plates and close a circuit, substantially as described.

3. A combined window-stop and alarm comprising a pivotally-mounted stop, a pin slidably mounted in a hole in the stop, a plate arranged on the stop on either side of the hole, and a point on the pin arranged to engage the plates and close a circuit, substantially as described. 35

4. An alarm comprising a pivotally-mounted stop arranged to engage with a door, a pin slidably mounted in the stop, a lug on the pin arranged to slide in a slot in the stop, and to hold the pin in place, and a plate arranged on either side of the pin and adapted to be engaged thereby, whereby the circuit is closed, substantially as described. 40

5. An alarm comprising a pivotally-mounted stop arranged to engage with a door, a pin slidably mounted in the stop, a lug on the pin arranged to slide in a slot in the stop, and to hold the pin in place, and a plate arranged on either side of the pin and adapted to be engaged thereby, whereby the circuit is closed, a battery, a bell, wire connections between the battery and bell and leading to the plates so that when the circuit is closed the bell is sounded, substantially as described. 45

In testimony whereof we hereunto affix our signatures in presence of two witnesses.

WILLIAM GILES.
HENRY RAMSEY.
